UNITED STATES PATENT OFFICE.

GEORGE D. CLAPP, OF BOSTON, MASSACHUSETTS.

SOLE-LEATHER-CUTTING MACHINE.

SPECIFICATION forming part of Letters Patent No. 734,819, dated July 28, 1903.

Application filed August 11, 1902. Serial No. 119,191. (No model.)

To all whom it may concern:

Be it known that I, GEORGE D. CLAPP, of Boston, county of Suffolk, State of Massachusetts, have invented an Improvement in Sole-Leather-Cutting Machines, of which the following description, in connection with the accompanying drawings, is a specification, like characters on the drawings representing like parts.

- 10 This invention relates to sole-leather-cutting machines, and has for its object to provide what is commonly called a "beam" sole-leather-cutting machine with suitable means especially adapting it for cutting out welts 15 for boots and shoes—such, for instance, as shown in my application for Letters Patent, Serial No. 62,909, filed June 3, 1901, yet many of the features herein to be described are applicable to the machine when used for cutting out other things. The welt shown in 20 said application consists of a strip of leather of uniform width, cut to comprise a semicircular toe portion and a pair of straight side portions extending in parallelism from the 25 extremities of said toe portion, the ends of said side portions being tapered, and this particular form of welt can be cut out of whole stock or large pieces without waste, the several welts nesting together as they are cut.
- 30 The machine embodying this invention comprises a cutting-bed, a beam movable toward and from said bed, suitable work-engaging devices for holding the material flat upon the cutting-bed, or, at least, as flat as 35 possible, and means for holding the material against sidewise movement on the bed; also, a suitable knife or set of knives for cutting out the welts borne by a suitable carrier, which is adapted to be moved along a track 40 and held securely in different positions thereon, said track being formed on the movable beam, so that as the beam is operated the knives will be moved toward the cutting-bed to cut out the welts; also, a suitable finder located beside the knives, which consists, essentially, of a blade adapted to be thrust into the slit cut by one of the knives, which acts to assist in correctly locating the knife-support and also in holding the work from 45 crowding away from the knives while they penetrate the material.

Figure 1 shows in front elevation a sole-

leather-cutting machine embodying this invention. Fig. 2 is a vertical section of the machine shown in Fig. 1, taken on the dotted line 2 2, the knives and support therefor being omitted. Fig. 3 is the under side view of the set of knives and plate to which they are attached. Fig. 4 is the vertical section of a portion of one of the knives and its support. Fig. 5 is the detail showing the work-securing device, which prevents sidewise movement of the material. Fig. 6 is the side elevation of the knife support or carriage. Fig. 7 is the vertical section of the knife support or carriage shown in Fig. 6, taken on the dotted line 7 7. Fig. 8 is a diagram showing in full and dotted lines the slits made in the material by two succeeding strokes of the knives, and Fig. 9 is a plan view of one of the welts. *a* represents the cutting-bed, which is suitably supported by the machine-frame.

b represents the beam, which is connected to the upright longitudinally-movable posts or supports *b'*, which have their bearings in the machine-frame, there being two such posts at each end of the beam. The posts at each end of the beam are connected together by a cross-piece *b''*.

c represents the main power-driven shaft, having its bearings in the machine-frame. To this shaft two eccentrics, as *c'*, are secured, upon which usual straps *c''* are placed, from which eccentric-rods *c'''* project downwardly, said rods being loosely or pivotally connected to the cross-pieces *b''*.

As the main shaft is revolved the beam *b* is moved toward the cutting-bed and then raised or restored to its normal elevated position.

So much of the machine herein to be described is of usual construction, and so also is the treadle-controlled clutch mechanism by which the main shaft is prevented from making but a single revolution each time it is started. I desire it to be understood, however, that while I have herein selected this well-known form of sole-leather-cutting machine as one well adapted to have the attachments embodying my invention applied to it, yet any other well-known suitable sole-leather-cutting machine may be employed so far as my invention is concerned.

To accurately cut out the welts or other

things, it is important that the material shall be laid flat upon the cutting-bed, and to produce this result I have provided a pair of horizontal bars d e , which extend lengthwise 5 of the machine above the cutting-bed, and means for moving them independently toward the cutting-bed and into engagement with the material on the bed. These bars therefore serve as work-engaging devices. 10 These bars are located a suitable distance apart to provide ample space between them for the knives. The ends of the bars d e enter and work up and down in guideways d' e' , which are made as vertical grooves in plates d^2 e^2 , which are secured to the machine-frame. As herein shown, these plates each have two parallel guideways, so that the bars may be placed in either of said guideways at will. The bar d has connected to it 15 at or near each end a link d^3 , which is loosely connected to one end of a lever d^4 , pivoted at d^5 , the opposite end of said lever d^4 being loosely connected by a link d^6 with the short arm d^7 , secured to a rod or bar d^8 , having its 20 bearings in the machine-frame. The rod or bar d^8 extends horizontally lengthwise the machine to provide for connection therewith of the means for actuating the bar d at each end. One end of the rod or bar d^8 projects 25 beyond the machine-frame and has secured to its outer projecting end a hand-lever d^9 , by which said rod or bar will be operated. On the outside of the machine-frame a ratchet-toothed plate d^{10} is secured, the teeth of which 30 are adapted to be engaged by said hand-lever d^9 , to thereby hold said hand-lever positively in whatever position it may be set.

To depress the bar d into engagement with the material on the bed, the hand-lever d^9 is 40 correspondingly depressed.

The bar e has connected to it at or near each end a spring e^3 , which extends downwardly on the inside of the machine-frame, and the lower end of said spring is loosely 45 connected to a short arm e^4 , projecting from the rod or bar e^5 , having its bearings in the machine-frame.

The rod or bar e^5 extends horizontally lengthwise the machine to provide for the 50 connection thereof with the means for actuating the bar e at each end. One end of said rod or bar e^5 projects beyond the machine-frame and has secured to its outer projecting end a hand-lever e^6 , by which said rod or bar 55 may be operated.

On the outside of the machine-frame a ratchet-toothed plate e^7 is secured, the teeth of which are adapted to be engaged by said hand-lever e^6 , to thereby hold said hand-lever 60 in whatever position it may be set.

To depress the bar e into engagement with the material on the bed, the hand-lever e^6 is correspondingly depressed. The material having been placed on the bed, first one of 65 said bars is brought into engagement with it and then the other and the material thereby laid flat upon the bed.

I do not limit my invention to the particular construction of the work-engaging devices herein shown and described, as it is obvious 7c that many forms of work-engaging devices capable of accomplishing substantially the same results may be employed, which come within the spirit and scope of this invention, the main object being to hold the work flat 75 upon the cutting-bed. It is also necessary to positively hold the material against sidewise or endwise movement on the bed, even while laid flat and held upon the bed by said work-engaging devices, and to accomplish this result a work-engaging device is provided, 80 which, as herein shown, (see Fig. 5,) consists of one or more awls, two being herein shown, attached to a lever f' , pivoted at f^2 to an ear f^3 , rising from a yoke f^4 , which straddles the 85 bar d , and is adjustably secured to said bar by a set-screw f^5 . The lever f' is formed or provided with a hand-lever or extension f^6 , by which it may be operated. The awls are designed to penetrate the leather or other material and enter the wooden cutting-bed, and thereby positively hold the material from sidewise or endwise movement on the bed, yet such device does not operate to any appreciable extent to hold the material flat upon 95 the bed only at the particular part thereof penetrated by the awls. This work-securing device is adjustable along on the bar d , so that it may be brought into position to engage pieces of leather of different widths or 100 lengths.

The work-securing device is attached to the bar d simply for convenience, as an independent support may be provided for it, if desired.

The knives herein shown for cutting out the 105 welts comprise several blades arranged as a set or gang, as shown in Fig. 3, each blade cutting a portion of the welt, which is shown in Fig. 8. As shown in said Fig. 3, three 110 blades are provided, one, as 2, and another, 110 as 3, which are made alike, or approximately so, each comprising a semicircular portion and two parallel side portions, one of which is made longer than the other, and a third blade, as 4, comprising two semicircular portions and three parallel side portions, and said 115 several blades are attached to a plate g and arranged in the manner shown, so that each time they are caused to penetrate the material the slits or cuts thereof will be continuous and several welts produced or cut out.

In Fig. 8 the full lines represent the slits or cuts produced by the first stroke of the knives and the dotted lines the slits or cuts produced by the second stroke, and on the 125 first stroke parts of four welts are produced, and on the second stroke likewise parts of four welts are produced, although in conjunction with the first stroke two complete welts are produced, and for each stroke thereafter two complete welts will be produced.

The blades 2, 3, and 4 project downwardly from the base-plate g any suitable distance, and between them flat-surfaced presser-

plates 5 are located, which are supported at a distance from the base-plate just beyond the cutting edges of the blades, so as to strike the material in advance of the blades. These 5 presser-plates serve to not only assist in holding the material flat on the cutting-bed, but also as an ejector.

The base-plate *g*, bearing the knives, is secured to a frame *h*, which is made as a carriage to slide along on a suitable track provided for it.

h' represents the truck-wheels, and *h*² *h*² the tracks on which said wheels run, said tracks being formed on the beam *b*. The carriage 15 bearing the knives is thus supported by said beam, and consequently rises and falls with said beam.

In order that the successive strokes of the knives shall cut the material in continuous lines and completed welts be thereby produced, it is necessary that the carriage bearing the knives shall be positively located and accurately held in its different positions along the track, and to accomplish this result a suitable locking device is provided for the carriage adapted to be operated by hand.

The locking device herein shown, which is one of many which may be employed, consists of a vertical pin *i*, (see Fig. 7,) set in the frame of the carriage and normally projecting above it, which is adapted to enter any one of a series of notches *i'* formed in a bar *i*², secured to the under side of the beam *b*. The pin is pressed into engagement with the notches by a spring *i*³. To disengage the pin *i*, a shaft *j* has its bearings in the carriage-frame, to which a short arm *j'* is secured, which engages the lower end portion of the pin *i*, and said shaft has secured to it 40 a hand-lever *j*², by which it may be rocked to thereby depress the spring-controlled pin.

The carriage when disengaged or unlocked is moved along by means of the hand-lever *k*², attached to it.

45 To assist in accurately locating the knives and also to prevent crowding aside of the material as it is cut, a blunt-edged blade or plate *m* is provided, which acts as a finder and which is adapted to be thrust into one of the 50 slits produced by the previous stroke of the knives, preferably the last slit next the uncut material, and said blade or finder by thus entering said slit holds the material and assists in accurately locating the knives. The blade *m* or finder is attached to the frame *m'*, which slides up and down in grooves formed by the plates *m*², attached to the carriage, and said frame *m'* has a lug *m*³, beneath which an arm *m*⁴ projects, which is attached to the rod 55 or bar *j* and is consequently operated by the hand-lever *j*². Whenever said hand-lever is moved to release the locking-pin *i*, the blade *m* will be raised free from the work, and whenever said hand-lever is restored to its 60 normal position the blade *m* will be allowed to fall and enter the slit.

Having thus described my invention, what

I claim as new, and desire to secure by Letters Patent, is—

1. In a sole-leather-cutting machine, the 70 combination of a cutting-bed, a beam movable toward and from said bed, and a work-securing device for holding the material against sidewise movement on the bed, substantially as described.

75 2. In a sole-leather-cutting machine, the combination of a cutting-bed, a beam movable toward and from said bed, one or more awls and an awl-carrier, and means for operating them to penetrate the material on the 80 bed and thereby hold it against sidewise movement, substantially as described.

3. In a sole-leather-cutting machine, the combination of a cutting-bed, a beam movable toward and from said bed, a work-engaging 85 device for holding the material flat upon the bed, and a work-securing device for holding the material against sidewise movement on the bed, substantially as described.

4. In a sole-leather-cutting machine, the 90 combination of a cutting-bed, a beam movable toward and from said bed, a work-engaging device for holding the material flat upon the bed, and a work-securing device for holding the material against sidewise movement 95 on the bed, which is borne by said work-engaging device, substantially as described.

5. In a sole-leather-cutting machine, the combination of a cutting-bed, a beam movable toward and from said bed, a work-engaging 100 device for holding the material flat upon the bed, and a work-securing device adjustably attached to said work-engaging device, for holding the material against sidewise movement on the bed, substantially as de- 105 scribed.

6. In a sole-leather-cutting machine, the combination of a cutting-bed, a beam movable toward and from said bed, a knife, a carriage supporting it, a movable blade, *m*, borne 110 by said carriage, and means for moving it, substantially as described.

7. In a sole-leather-cutting machine, the combination of a cutting-bed, a beam movable toward and from said bed, a knife, a carriage supporting it, a blade, *m*, borne by said 115 carriage and means for moving it independently of the beam, substantially as described.

8. In a sole-leather-cutting machine, the combination of a cutting-bed, a beam movable toward and from said bed, a knife, a carriage supporting it, and means, borne by said carriage, for engaging the cut portion of the leather before the knife is operated, substantially 120 as described.

9. In a sole-leather-cutting machine, the combination of a cutting-bed, a beam movable toward and from said bed, a knife, a carriage supporting it, tracks on the beam on which said carriage moves, a notched bar on 125 said beam, a spring-controlled locking-pin on the carriage and means for operating said locking-pin consisting of an arm, a rock-shaft to which it is attached, and a hand-lever at-

tached to said rock-shaft, substantially as described.

10. In a sole-leather-cutting machine, the combination of a cutting-bed, a beam movable toward and from said bed, a knife, a carriage supporting it, a movable blade *m* borne by said carriage, means for moving it, a locking device for said carriage, and means for operating it connected with the means for operating said blade *m*, substantially as described.

11. In a sole-leather-cutting machine, the combination of a cutting-bed, a beam mov-

able toward and from said bed, a knife, a carriage supporting it, a movable blade, *m*, borne by said carriage, a locking device for said carriage, and means for simultaneously operating said blade and locking device, substantially as described.

In testimony whereof I have signed my name to this specification in the presence of two subscribing witnesses.

GEORGE D. CLAPP.
